United States Patent Office

Des. 175,295
Patented Aug. 9, 1955

175,295

COMBINED RANGE TOP UNIT AND SHELF

Robert H. Caldwell, Lookout Mountain, Tenn.

Application February 24, 1954, Serial No. 29,184

Term of patent 3½ years

(Cl. D81—25)

The single figure is a perspective view of a combined range top unit and shelf, showing my new design, the other side of the shelf being like the side shown.

I claim:

The ornamental design for a combined range top unit and shelf, substantially as shown and described.
